US0D1079629S

(12) **United States Design Patent** (10) **Patent No.:** **US D1,079,629 S**
(45) **Date of Patent:** **** Jun. 17, 2025**

(54) **WIRELESS CHARGER**

(71) Applicant: **GUANYU (DONGGUAN) INTELLIGENT TECHNOLOGY CO., LTD.**, Guangdong (CN)

(72) Inventor: **Shoufeng Yi**, Guangdong (CN)

(73) Assignee: **GUANYU (DONGGUAN) INTELLIGENT TECHNOLOGY CO., LTD.**, Dongguan (CN)

(**) Term: **15 Years**

(21) Appl. No.: **29/968,494**

(22) Filed: **Oct. 16, 2024**

(30) **Foreign Application Priority Data**

Sep. 18, 2024 (CN) 202430593075.X

(51) **LOC (15) Cl.** **13-02**

(52) **U.S. Cl.**

USPC **D13/108**

(57) **CLAIM**

The ornamental design for a wireless charger as shown and described.

DESCRIPTION

FIG. 1 is a perspective view of a wireless charger showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the wireless charger in a different configuration; and,

FIG. 10 is a perspective view of the wireless charger where the wireless charger is in a folded state.

The broken lines in the drawings depict portions of the wireless charger that form no part of the claimed design.

1 Claim, 10 Drawing Sheets
